UNITED STATES PATENT OFFICE.

WILFRED P. CARSON, OF GREENSBORO, NORTH CAROLINA.

ATTACHMENT FOR GRAIN OR GRIST MILLS.

1,327,700.

Specification of Letters Patent. Patented Jan. 13, 1920.

Application filed March 24, 1919. Serial No. 284,611.

To all whom it may concern:

Be it known that I, WILFRED P. CARSON, a citizen of the United States of America, and resident of Greensboro, county of Guilford, 5 State of North Carolina, have invented certain new and useful Improvements in and Relating to Attachments for Grain or Grist Mills, of which the following is a specification.

10 This invention relates to certain improvements in attachments for grain grinding mills, or what are commonly called corn or grist mills; and the objects and nature of the invention will be readily understood by 15 those skilled in the art in the light of the following explanation of the accompanying drawings illustrating what I now believe to be the preferred embodiment or mechanical expression of my invention from among 20 other forms, arrangements, and combinations within the spirit and scope thereof.

An object of the invention is to provide improved means for feeding the grain to the mill and at the same time separating foreign 25 material and objectionable matter from the grain, whereby the grain while being transferred from the mill hopper to the grinding surfaces will be cleansed of objectionable and foreign matter likely to cause injury to 30 the grinding surfaces or to lower the quality of the meal.

A further object of the invention is to provide certain improvements in vibrating shoes for corn and other grist mills.

35 A further object of the invention is to provide certain improvements in details of construction and in arrangements of parts for the production of an advantageous and improved grist mill.

40 The invention consists in certain novel features in construction and in combinations and arrangements as more fully and particularly set forth hereinafter.

Referring to the accompanying drawings:—

Figure 1, is a side elevation of a grain grinding mill, partially in vertical section and with parts broken away.

Fig. 2, is a detail perspective of the feed 50 shoe.

Fig. 3, is a detail perspective of the screen slide of the feed shoe.

Fig. 4, is a cross section of the feed shoe.

Fig. 5, is a detail perspective of the feed 55 box looking at the inner side thereof.

Fig. 6, is a detail perspective of a portion

of the feed shoe looking at the under side thereof.

In the drawings, I show any suitable corn or other grain grinding mill, preferably of 60 the horizontal - spindle vertically - rotating bur type, having any suitable source of grain supply, usually a hopper 6, terminating in a depending spout or nozzle 60 from which the grain falls by gravity onto a suitable inclined 65 vibrating shoe arranged above the mill casing 1. The grain travels down the shoe and in the instance illustrated, falls from the rear end thereof into means arranged beyond one end of the mill casing 70 and designed to deliver the grain into the feed passage 3 of the mill, through which the grain is forced by worm 5 to the grinding faces of the stones or burs. The worm 5 is carried by the mill spindle 2 which also 75 carries and drives the rotary stone or bur of the mill.

Any suitable driving means, such as pulley 2^a can be provided for rotating the mill spindle 2.

The hopper 6 rests in and is upheld by a suitable supporting structure fixed to the top of the mill casing and rising therefrom. This supporting structure in the specific example illustrated, consists of a horizontal 85 top ring 61 and several spaced standards or legs 62 to the upper ends of which the ring 61 is fixed. The lower ends of the legs 62 have suitable feet 63 fixed on the top of the mill casing. The hopper rests on and is 90 centered and supported by the ring 61 and depends therethrough so that the nozzle 60 is held in operative position with respect to and above the shoe. The feed regulator comprises the vertically movable gate or 95 regulator sleeve 64, that co-operates with the grain board 14 of the shoe to cut off and control the flow of grain from nozzle 60. Suitable means are provided to adjust said gate vertically.

The shoe is arranged above the mill casing and is longitudinally inclined from its grain receiving end to its discharge end. This shoe can be supported and vibrated in any desirable manner and by any suitable 105 means. For instance, I show a suitable bracket 7 fixed to and projecting from the mill casing; a vertically swingable lever 7^a fulcrumed to said bracket; a plate spring 8 forming the operative connection between 110 a rounded enlargement 7^b on said lever and the rear end of the shoe; and an eccentric

on the spindle 2 having its eccentric strap 9 provided with upright pitman 10, operatively coupled to the free end of the lever 7^a by a loose or flexible coupling 11.

5 The shoe of my invention comprises a longitudinally elongated box having a bottom floor 13 and a surrounding edge wall 12 closing the box or housing at the ends and longitudinal sides, except for an opening at 10 the upper end, as hereinafter described, through which the screen slide is entered and withdrawn. The box is open at the upper side between the depressed grain board or plate 14, the stop or deflecting dam or 15 board 15, and the longitudinal opposite edge strips 16. These boards or plates 14 and 15 and the edge strips 16, are fixed and arranged over the hollow or interior chamber of the shoe and said top opening of the shoe 20 is bounded by the longitudinal edges of the strips and the transverse grain delivering edge of the plate 14 and the V shape deflecting edge 15^a of the plate 15.

On the floor 13 of the shoe is arranged a 25 fixed or permanent dam or block 17 closing the lower end of the space within the box and having a V-shape deflecting edge 17^a leading to the two separated bottom outlets 18 through the floor 13 for discharge of 30 screenings. This stop or dam 17 is formed with a central passage registering with a central passage through floor 13 located between openings 18, and these passages form the grain discharge or outlet 19 from the 35 space between the top plate 15 and the dam 17.

Within the interior of the box or shoe, I provide a pair of longitudinal slideways or 40 drawer supports and guides 20 arranged along the longitudinal opposite edge portions of the interior of the shoe but spaced inwardly from the side edge walls of said box. In the example shown, each guide consists of an angle iron providing a longitudinal upstanding flange and a longitudinal 45 horizontal or depressed flange and these angle irons are fixed in the box or shoe and spaced downwardly from the overhanging top strips 16 and upwardly a distance above 50 the bottom floor 13.

These guides 20 are arranged to receive the longitudinally removable screen drawer or slide which is applicable to and removable from the box or shoe through a slot or 55 opening 21 in the upper end edge wall of the box. The screen drawer or slide consists of a rigid open frame composed of cross head or upper end 22, the opposite cross head 23, and the longitudinal edge strips 24; and upper and lower fixed parallel reticulated sheets or screens 25, 26, fixed to and covering the upper and lower sides of said open frame and spanning the opening inclosed thereby. The upper screen 25 is of 65 relatively coarse mesh to permit passage of

the grain, while the lower screen 26 is of relatively fine mesh to uphold and support the perfect or full sized grains and prevent passage thereof through the screen while permitting dirt and small pieces of foreign matter to separate from the grain and fall through said fine screen. The upper or coarse screen is designed to separate coarse refuse and foreign material from the grain and uphold the same from the grain which 70 falls through onto the lower fine screen. The space between the upper and lower screens is of sufficient width vertically to permit free travel of the grain along the top surface of the fine screen to a vertical central outlet 27 at the lower end of the screen and opening downwardly through the cross head 23. This outlet is closed at the top by the top or coarse screen, while the framework of the screen slide forms downwardly 75 converging guide edges or walls 23^a, for guiding and leading the grain to said bottom outlet.

The screen slide is formed to slip longitudinally into the shoe or box through the 80 end opening 21 and the outer end of the slide head 22 is provided with a flange or plate 28 to exteriorly close said opening, and with a pull handle 29 whereby the slide can be conveniently drawn from the 85 shoe. The slide occupies approximately the full length of the box, and throughout its length rests on the horizontal flanges of the guides 20 and between the vertical flanges of said guides. This slide fits the under surfaces of the plates 14 and 15 and the top surface of the dam 17, and the bottom discharge opening 27 of the screen slide registers with the grain discharge or bottom outlet 19.

While the length of the screen slide 90 approximately equals the length of the box or shoe, the width of said slide is less than the interior width of said box and only equals the distance between the vertical flanges of the fixed guides 20. These guides are spaced 105 upwardly from the floor 13 and inwardly from the edge walls 12 of the shoe, and hence vertical spaces or passages 20^a exist between walls 12 and the guides 20 leading from the spaces above said guides to the horizontal 110 spaces between the floor 13 and bottom surfaces of said guides. In other words, material is free to drop behind said guides to the floor and is free to move on the floor below the guides. These spaces above, behind and 115 below the guides are utilized for the passage of the refuse from the top of the coarse screen to the floor 13 and its final discharge through bottom outlets 18 from said floor. To permit passage of the refuse from the 120 coarse screen 25, I provide opposite side lateral outlets 20^b under the side strips 16 and in outward continuation of the diverging guide edges 15^a of dam 15 and over and 125 beyond the side edges of the screen slide and 130

the guides 20 and opening to the spaces 20^a. The refuse on the coarse screen 25 will hence gradually work down that screen until it strikes the diverging guide edges 15^a and 5 will be thereby guided laterally to the outlets 20^b through which it will pass on the screen slide until it drops from the edges of that slide falling in the spaces behind the guides 20 onto the floor 13. The refuse on 10 this floor, from the outlets 20^b and from the fine screen 26, gradually works toward the lower end of the floor and into contact with the diverging guide edges 17^a which direct the same to the bottom outlets 18 through 15 which the screenings or refuse fall from the box or shoe. The grain retained on the fine screen gradually works toward the lower end of the screen slide where it is guided by the converging guide edges 23^a and passes 20 over the lower edge of the fine screen and drops through opening 27 and outlet 19 from the box or shoe.

When in operative position within the shoe or box, the screen slide is in effect a 25 fixed part of the shoe, and yet can be readily removed for cleaning and to permit access to the interior of the shoe or to permit replacement by a similar screen slide having screens of different mesh or sizes.

30 Certain advantages in structure and operation are gained by this screen slide and shoe formation and arrangement. The lower end of the shoe or feed box is slidably upheld or supported in any suitable manner 35 and projects outwardly beyond the mill casing, and overhangs an intake box 30 for leading the grain to the feed passage or box 3 and for discharging the screenings at the exterior of the mill casing.

40 In the example illustrated, this box 30 consists of a casting or other housing arranged vertically at the exterior of the mill casing and secured thereto. The box is composed of a vertical exterior wall at its inner 45 side formed with several vertical spaced flanges 30^c arranged so that their inner vertical edges fit the mill casing and form a vertical grain chute or passage 30^a, and two vertical screenings chutes or passages 30^b.

50 This intake box is open at its upper end which is located under the outer end of the shoe, and is so arranged that the grain outlet 19 of the shoe is always aligned with and over the open upper end of grain chute 30^a, and the screenings outlets 18 register with 55 and are always over the upper ends of the screenings chutes 30^b respectively.

At its lower end, the intake box is so formed that its grain chute 30^a fits and opens 60 into the feed passage or box 3 of the mill to deliver the cleaned grain thereto, while the lower ends of the screenings chutes 30^b open outwardly to discharge at the exterior of the casing.

65 It is evident that various changes, modifi-

cations, and additions might be resorted to without departing from the spirit and scope of my invention, and hence I do not wish to limit myself to the exact disclosures hereof.

What I claim is:—

1. In a grist mill feed mechanism embodying a vibratory shoe for cleaning the grain from the hopper and delivering the cleaned grain to the intake box for passage to the mill feed box; said shoe comprising a hollow box having passages and separate outlets for the grain and screenings and fixed top and bottom boards, and a longitudinally removable screen slide embodying a frame and upper and lower screens, said screen 80 slide being arranged between said top and bottom boards, said box providing a longitudinal guideway for said slide and an end wall closed except for an opening for the insertion and removal of said slide, said slide 85 closing said opening.

2. A grain feed shoe or box comprising a housing having a bottom floor with separate vertical grain and screenings outlets there-through at one end thereof, a dam on the 90 box floor closing the same from the grain outlet and providing passages to the screenings outlets, an upper coarse screen and a lower fine screen, a dam on the coarse screen providing guideway edges, said box providing lateral screenings outlets above the coarse screen and along said guiding edges and vertical passages from said lateral outlets and beyond the vertical edges of the screens to said floor, and means providing a 100 grain discharge from the fine screen to said grain outlet.

3. A grain feed shoe or box having a bottom floor to receive the screenings and a discharge therefor, an upper coarse screen 105 and a lower fine screen in said box, means providing a grain passage from the fine screen and a grain outlet therefor from the shoe, and means providing opposite lateral outlets for the screenings from said coarse 110 screen, and vertical passages from said outlets leading to said floor and arranged beyond the side edges of said screens.

4. A grain feed shoe or box having a surrounding edge wall closing the lower or 115 front end of the shoe and having a bottom floor with separate outlets opening there-through for screenings and for grain, means closing the grain outlet from the screenings outlets and from the material on said floor, 120 coarse and fine screens in said shoe, means providing a grain passage from the fine screen to said bottom grain outlet, and means providing passages from the top surface of the coarse screen to said floor.

5. A grain feed shoe or box having a closed end wall with an opening and screen slide guides arranged longitudinally within the box and leading from said opening, a screen slide arranged longitudinally within 130

the box and closing said opening and longitudinally removable therethrough, said shoe providing internal vertical passages outwardly beyond said guides to receive material from the top surface of a slide screen and deliver the same into the shoe below said slide.

6. In grist mills and the like embodying a vibratory shoe for separating the grain from the refuse and delivering the grain and

refuse to separate chutes in an intake box for passage of the grain to the mill feed box and for discharge of refuse at the exterior of the mill; an intake box consisting of a vertical wall at its inner side having vertical flanges arranged so that their vertical edges fit the wall of the mill casing and thereby form the separate grain and refuse chutes. 15

WILFRED P. CARSON.
